United States Patent

Des. 237,928

Patented Dec. 9, 1975

237,928

SHOP DESK OR SIMILAR ARTICLE

Eugene R. Kent, Lombard, Ill., assignor to Draik
Midwest Company, Inc., Oak Brook, Ill.

Filed Nov. 27, 1974, Ser. No. 527,756

Term of patent 14 years

Int. Cl. D6—04

U.S. Cl. D6—162

FIG. 1

FIG. 4

FIG. 1 is a front, top and left side perspective view of a shop desk or similar article showing my new design; FIG. 2 is a top plan view; FIG. 3 is a front elevational view; FIG. 4 is a right side elevational view; and FIG. 5 is a rear elevational view.

I claim:

The ornamental design for a shop desk or similar article, substantially as shown and described.
